TELEVISION RECEIVER

Kurt Schlesinger, Berlin, Germany, assignor, by
mesne assignments, to Loewe Radio, Inc., a cor-
poration of New York

Application February 9, 1935, Serial No. 5,872
In Germany February 12, 1934

2 Claims. (Cl. 178—7.3)

In the television methods known per se, in which frame and line synchronizing impulses are transmitted as modulations of the same carrier wave with the image signals and exceed the latter in amplitude the following difficulties occur in practice:

It is assumed that a transmitter possesses the modulation curve shown in Fig. 1. Above the time axis T there is shown the course of the modulation potential, the potential 0 belonging to a grey image point. The image current modulation extends between the maximum and minimum values 1 and 2 , which correspond with light white and deep black in the picture. The curve during a line is, for the sake of comprehension, assumed to be a sine-wave 3 . After termination of a line there is transmitted a line impulse 4 , the sign of which is negative, i. e., is assumed to correspond with a black margin to the picture. This line impulse may extend to an ordinate 5 , and it is assumed that the same extends from the black value of the image modulation 2 to exactly the same extent into negative as the white value 1 extends into positive. To make the position more clear it is assumed that a very white image point is modulated with 5 volts positive potential, and a deep black image point with -5 volts, so that in view of the above remarks the line impulse requires to be passed to the transmitter with -15 volts.

It will be quite obvious that a difference in amplitude of this nature between the line impulses and the black in the image means nothing else than that a large proportion of the transmission energy is not utilised for the transmission, or in other words that the transmitter cannot be sufficiently modulated with the actual image contents 3 , viz., at the most to the extent of 50%. A considerable improvement would accordingly be obtained, if the difference in amplitude between the peak value of the line impulse and the peak value of the image impulse could be reduced. From a practical point of view, however, there is a limit in this direction involved by the unavoidable fluctuations in the transmission by the natural noises of the reception, by fluctuations in the total degree of amplification of the receiver and also by the limited separating efficiency of the amplitude filter.

In any case for reliable television operation an amplitude ratio of approximately 1:1 is shown in Fig. 1.

The invention consists in the use of non-linear amplifiers in the receiver furnishing to the amplitude filter signals with large difference in po-

tential according to Fig. 1, whereas the transmitter is modulated at a much lower degree and is accordingly better utilized.

Figs. 1, 2 and 3 are explanatory diagrams, while

Fig. 4 is a specific embodiment of applicant's invention.

Fig. 2 serves to make the matter more clear. In the same there is shown a curved amplifier tube characteristic 6 . If an amplifier of this nature is furnished with a voltage-time curve according to Fig. 1, there is obtained a distortion. To simplify matters the curved characteristic 6 is replaced by two straight lines $6'$ and $6''$, and there is obtained an image modulation $3'$ and a line impulse $4'$ with a much smaller difference in amplitude than in the primary curve. Apparently, therefore, with a characteristic in the form of 6 there is accomplished exactly the opposite to that which was sought to be attained. A characteristic of this nature belongs in practice to a negatively biassed anode bend rectifier without grid current. The same may be referred to as a convex characteristic.

In Fig. 3 there is shown the counterpart there-
to, viz., a concave characteristic. The charac-
teristic itself is designated 7 , and is replaced by
the two tangents $7'$ and $7''$. An amplifier of this
nature produces the amplitude diagram $3''$ and
 $4''$. In this arrangement the difference in ampli-
tude between line impulse and contents of the
image is evidently considerably increased, i. e.,
the desired variation in scale practically attained.

In the case of transmitters with modulation
reverse to that of Fig. 1, in which, therefore,
the synchronisation signals exceed in positive di-
rection the image modulation, as have already
become known in practice a reversal of these con-
ditions takes place and a characteristic accord-
ing to Fig. 2 has to be used.

The practical execution of this method is ex-
plained by Fig. 4. There is assumed to be a tele-
vision transmitter, which operates with negative
line impulses and possesses merely a small ex-
cess of amplitude between synchronising signal
and image signal, i. e., a transmitter which is
well utilised and is modulated with the image
current to the extent of approximately 80% and
with the synchronising signals to the extent of
approximately 100%. The receiver is a super-
heter, which receives with an aerial 8 , converts
by means of a local oscillator 9 the ultra-short
wave picked up into a comparatively long inter-
mediate wave, and amplifies the latter in an in-
termediate-frequency amplifier 10 . Up to now a

total characteristic is assumed which is strictly linear. Linear operation is also assumed to exist in the rectifier 11, so that the signalling potentials passed to the intensity control electrodes of 5 the television tube 12 are correctly proportioned to the transmitter modulation amplitudes. The amplitude filter, which is intended to separate the synchronising signals from the image signals, is a gas-filled diode 13 with hot cathode 14 and 10 anode 15. Its cathode is connected to the relaxation oscillator to be synchronised. According to the invention there is provided between the detector output 16 and this filter tube 13 an amplifying tube 17 with suitably curved (concave) characteristic, which causes an amplifying variation in scale in favour of the synchronising signal, in accordance with Fig. 3. A characteristic of this nature may be given to the tube by utilising the grid current. For this purpose 15 the control grid 18 of the tube 17 is not furnished with a negative bias, but is connected to the cathode in direct fashion through the medium of a leakage resistance 19. A grid condenser 20 requires to be so small that the same 20 together with the resistance 19 possesses a time constant of approximately the time occupied by the transmission of one image point. It is then, and only then, that the characteristic of the tube 17 becomes concave even in respect of the shortest impulses 4. Otherwise there results owing to 25 too slow discharge of the grid charge a frequency-dependency of the effective transmission characteristic of 18 in the form of a weakening of the high frequencies. Since the synchronising signals which are concerned endure only for a few 30 image points, i. e., belong to the shortest signals which are transmitted at all, values of 20=25 mmf. and 19=10,000 ohms with a time constant of a few microseconds are necessary and sufficient. The anode resistance 21, inasmuch as no 35 amplification is desired, must cause no change in phase at maximum frequency, i. e., amount to approximately 1000 ohms.

In the case of a positively modulated transmitter there is imparted a negative bias to the 40 control grid so that the valve is operating like an anode bend rectifier, and the considerations with regard to the inertia of the grid circuit do not apply.

45 It is possible to unite structurally the two tubes 17 and 13. For this purpose it is of course necessary to remove the gas-filling of 13, and the loss in separating efficiency thus incurred must be counter-balanced by a but slight amplification in the tube 17. For this purpose a somewhat larger 50 anode resistance 21 of approximately 5000 ohms is necessary and sufficient. The scale-varying element 17 may be replaced by imparting to the detector 11 a concave characteristic, or to one of the final tubes of the carrier-frequency 55 amplifier 10, by means of a grid-current effect like to valve 17 in the drawing. The amplitude scale of the image signals is then somewhat falsified.

60 I claim:

1. A television system adapted to receive a radio frequency carrier modulated by a series of picture and synchronizing signals where the synchronizing signals are transmitted at substantially maximum carrier intensity and where the picture signals are transmitted at values within the range between substantially zero to sub-

stantially 80% maximum carrier intensity comprising means to receive and amplify the received carrier, means to demodulate the carrier to produce detected picture and synchronizing signals with the ratio of the strongest picture signals to the synchronizing signals being of the order of approximately 4 to 5, means for applying the detected picture and synchronizing signals to a picture producing device, an electron discharge tube having a cathode, a control electrode and an anode, a resistance connecting the control electrode to the cathode of the tube, means including a relatively low capacity condenser connected to said control electrode for applying the detected picture and synchronizing signals to the control electrode, the values of the condenser and resistance being such that their time constant is of the order of the time required to transmit one picture element, the value of the resistance being relatively low whereby a non-linear concave control electrode potential-anode current characteristic will result, means including a load circuit for maintaining said anode positive with respect to said cathode whereby picture and synchronizing signals will appear at the anode in distorted form with respect to the applied signals, the distortion caused by the non-linear characteristic resulting in an attenuation of the picture signals and a change in the ratio of the picture to synchronizing signals to at least the order of one to one whereby a separation of the picture signals from the synchronizing signals may be more readily accomplished, and means for separating the synchronizing signals from the picture signals for synchronizing purposes.

2. A television system adapted to receive a radio frequency carrier modulated by a series of picture and synchronizing signals where the synchronizing signals are transmitted at substantially maximum carrier intensity and where the picture signals are transmitted at values within the range between substantially zero to substantially 80% maximum carrier intensity comprising means to receive the received carrier, means to demodulate the carrier to produce detected picture and synchronizing signals with the ratio of the strongest picture signals to the synchronizing signals being of the order of approximately 4 to 5, an electron discharge tube having a cathode, a control grid and an anode, a resistance connecting the control grid to the cathode of the tube, means including a relatively low capacity condenser connected to said control electrode for applying the detected picture and synchronizing signals to the control grid, the values of the condenser and resistance being such that their time constant is of the order of from two to five micro-seconds, the value of the resistance being relatively low whereby grid current may flow and whereby a non-linear concave grid potential-anode current characteristic will result, means including a load circuit for maintaining said anode positive with respect to said cathode whereby picture and synchronizing signals will appear at the anode in distorted form with respect to the applied signals, the distortion caused by the non-linear characteristic resulting in an attenuation of the picture signals and a change in the ratio of the strongest picture signals to the synchronizing signals from approximately 4 to 5 at least the order of unity.
